CLAIM

The ornamental design for a barbecue implement with wood laminate handle, as shown and described.

DESCRIPTION

FIG. 1 is a front elevational view of a barbecue implement with wood laminate handle showing my new design, the rear elevational view being a mirror image thereof;

FIG. 2 is a left side view thereof;

FIG. 3 is a right side view thereof;

FIG. 4 is the opposite side of the right portion of the handle shown in FIG. 3, the opposite side of the left portion of the handles shown in FIG. 2 being a mirror image thereof;

FIG. 5 is a top plan view of the left portion thereof, the bottom plan view being a mirror image thereof; and,

FIG. 6 is a top plan view of the right portion thereof, the bottom plan view being a mirror image thereof.

The broken lines are for illustrative purposes only and form no part of the claimed design.

Elements of the handle are shown separately in FIGS. 4-6 for clarity of illustration.
